CLAIM

The ornamental design for a bobbin, as shown and described.

DESCRIPTION

Fig. 1.1 is a perspective view of a bobbin showing applicant's design;

Fig. 1.2 is a perspective view of the bobbin of Fig. 1.1;

Fig. 1.3 is a back view of the bobbin of Fig. 1.1;

Fig. 1.4 is a bottom view of the bobbin of Fig. 1.1;

Fig. 1.5 is a front view of the bobbin of Fig. 1.1;

Fig. 1.6 is a left view of the bobbin of Fig. 1.1;

Fig. 1.7 is a right view of the bobbin of Fig. 1.1; and

Fig. 1.8 is a top view of the bobbin of Fig. 1.1.

The design relates to a metallic bobbin having embossed flanges for winding steel wires.
